STEAM GENERATOR

Gustav A. Rehm, Springfield, Ill., assignor to Springfield Boiler Company, Springfield, Ill., a corporation of Illinois

Application April 11, 1949, Serial No. 86,788

2 Claims. (Cl. 122—478)

My invention relates to an improvement in steam generators and has for one purpose to provide a generator or furnace of relatively large size and high rate.

Another purpose is to provide a steam generator in which, in a structure of large size and high rate, it is possible to keep the furnace temperatures below the fusing point of the slag or impurities in the fuel in order to prevent undue slagging or coating of the boiler tubes.

Another purpose is to provide an improved steam re-heater arrangement for such a furnace.

Another purpose is to provide an improved steam super-heater arrangement for such a furnace.

Another purpose is to provide a furnace of the above type in which a re-heater and a super-heater are arranged in a manner and location to increase the efficiency of the complete generator.

Other purposes will appear from time to time in the course of the specification and claims.

The invention is illustrated more or less diagrammatically in the accompanying drawing wherein I illustrate a vertical section of the invention.

Like parts are indicated by like symbols throughout the specification and drawing.

Referring to the drawing I illustrate a form in which, in a straight tube boiler, the superheater and the re-heater are generally vertically arranged, and at one side of the initial combustion chamber. It will be understood, however, that the superheater and re-heater tubes may be employed in the bent tube boiler designs, and may be arranged at any angle from horizontal to vertical, and may be supported in any desired manner.

Referring specifically to the drawing and to the re-heater and superheater portions, the re-heater tubes are illustrated at 100, with associated headers 101 and 102. The superheater tubes are indicated at 105, with connecting headers 106 and 107. 108 generally indicates the combustion chamber, which need not be described in detail. 31 indicates any suitable steam drum, and 31a is any suitable lower drum, the two drums being connected by any suitable tubes 31b, shown as generally vertical, with offset end portions for connection with the drums 31 and 31a. It will be noted that, at one side, the combustion chamber 108 is closed by a partition 110 having an upper edge portion defining an opening or passage 109 through which the heated products of combustion may flow. The superheater and re-heater tubes, as will be clear from the drawing, have connected portions on each side of the partition 110, the superheater and re-heater tubes being associated and extending in general parallelism. A downwardly extending flue passage is defined between the partition 110 and the partition 111. A third partition 112 extends downwardly from the drum 31, and between the tubes 31b, and the above described re-heater and superheater tubes.

It will be noted that transversely extending bottom partitions 111a and 112a define a passage which may be closed by a closure 114. The closure 114 is shown as in closed position. When in such position all the heated products of combustion are constrained to flow downwardly between the partitions 110 and 111 and then transversely below the partition 111a and upwardly about or beyond the end of the passage closed by the closure 114. At the first pass, above the drum 31a, the heated products of combustion flow through and about the lower ends of the tubes 31b. The heated gases may be constrained to a tortuous path through the tubes 31b by the

2

staggered transverse partitions 115, 116 and 117. 118 indicates any suitable flue outlet. It will be understood that when the opening 114 is opened, part of the heated gases may bypass the superheater and re-heater tube portions extending downwardly between the partitions 110 and 111, and may flow outwardly through the outlet between the transverse partitions 111a and 112a.

Although the diagrammatic illustration shows a straight tube boiler design, the principle of furnace division and placing of superheater and re-heater tubes applies to the bent tube boiler design equally as well, except that superheater and re-heater tubes may be arranged at any angle from horizontal to vertical, or pendant type, tube loop arrangement.

I illustrate a structure which is applicable to both straight and bent tube boilers. It is applicable to dual or multiple chamber furnaces. That is to say, whereas I illustrate only one combustion chamber, I could, under certain circumstances, employ more than one.

It will be understood that I may burn different fuels, but since the details of the boilers as such do not form part of the present invention, I illustrate, merely diagrammatically, nozzles 9a.

It will be understood that the above-described disposition of the superheater and the re-heater may be applied both to straight tube and to bent tube boilers, to single combustion chamber boilers, and to multiple combustion chamber boilers, whether the individual chambers are equal or unequal in size, and to differentially fired multiple chamber boilers.

As a matter of fact, since re-heaters are generally applied where pressure of over one thousand pounds is employed, my invention may be more universally applied to bent tube boilers than to straight tube boilers. However, vertical straight tube boilers are used at temperatures sufficiently high to render my arrangement of superheater and re-heater advantageous.

I claim:

1. In a boiler and a furnace therefor, a first partition, a front wall, parallel side walls and a roof defining a combustion chamber, said partition constituting the rear wall of said combustion chamber, the upper edge of said partition being spaced from the roof of said combustion chamber to define therewith an exit passage for the gases of said combustion chamber, a second partition spaced from said first partition and defining therewith a convection passage, means forming a floor for said latter passage, the lower edge of said second partition being spaced from said floor of said convection passage to define therewith an exit for said convection passage, a first group of superheater tubes positioned in an upper portion of said combustion chamber adjacent said combustion chamber exit passage, a second group of superheater tubes positioned in said convection passage, the tubes of the first and second superheater groups being connected through said combustion chamber exit passage above the upper edge of said first partition, a first group of re-heater tubes positioned in an upper portion of said combustion chamber adjacent said combustion chamber exit passage, a second group of re-heater tubes positioned in said convection passage, the tubes of said first and second re-heater groups being connected through said combustion chamber exit passage above the upper edge of said first partition, portions of the re-heater tubes of said first re-heater group being interlaced with portions of the superheater tubes of said first superheater group, portions of the re-heater tubes of said second re-heater group being interlaced with portions of the superheater tubes of said second superheater group, said interlaced portions of said first and second groups extending above and below the upper edge of said first partition.

2. The structure of claim 1 characterized by and including a third partition positioned between said first and second partitions, said third partition having an upper edge lying in substantially the same horizontal plane with said first partition, said third partition being spaced from said first partition and enclosing therebetween the lower portions of said second re-heater and superheater groups, said third partition being spaced from said second partition and defining therewith a substantially unobstructed

by-pass flue positioned to permit some of the gases flowing through said convection passage to by-pass said lower portions of said second reheater and superheater groups, said third partition including an end portion extending through said convection passage exit.
